UNITED STATES PATENT OFFICE

JOSEPH W. RAGAN, OF HANNIBAL, MISSOURI

ATTACHMENT FOR HAIR CLIPPERS

Application filed May 15, 1929. Serial No. 363,211.

This invention relates to an attachment for hair clippers particularly designed for use on electro-magnetically operated hair clippers.

An important object of this invention is to provide an attachment of the above nature which permits the barber to clip the hair with the magnetically operated hair clippers to cut the hair starting at the hair line on the neck, cutting the hair at about one-thirty-second of an inch long and tapering it upwardly in a uniform taper to one-quarter of an inch in length or longer if desired.

With attachments of this type as are now on the market, it has been found impossible to so cut the hair as before described, if the hair is fine or short or laid close to the scalp.

Another object of the invention is to provide an attachment for electro-magnetically operated hair clippers wherein the attachment is so formed as to prevent the hair from slipping beneath the lower teeth of the lower plate, since the said attachment is designed to be in close working relation with the teeth on the lower plate and yet does not interfere with the working arrangement of the clippers proper.

Another very important object of this invention is to provide an attachment of this character which is capable of being held in an adjusted position on the clippers, is exceedingly simple in its construction, easy to attach and detach, inexpensive to manufacture, thoroughly reliable and efficient in use and otherwise well adapted for cooperation with the clippers to enable the said clippers to do their work as they were intended and designed.

With the above and numerous other objects in view as will appear as the description proceeds, the invention resides in certain novel features of construction and in the combination and arrangement of parts as will be hereinafter more fully described and claimed.

In the drawings:

Figure 1 is a top plan view of a well known type of magnetically driven hair clippers showing my attachment associated therewith.

Figure 2 is a fragmentary side elevation

thereof having certain parts broken away to clearly illustrate the application of my invention in conjunction with the clippers.

Figure 3 is a top plan view of the invention per se.

Referring to the drawings in detail, it will be seen that the letter A designates a well known type of electro-magnetically driven hair clipper comprising among other parts, front stationary teeth 5, which cooperate with movable teeth 6 in the cutting operation.

Referring now in detail to my invention, it will be seen that the same is preferably constructed of a very light material such as metal and is designated generally by the reference character 7.

The attachment as herein illustrated is in the form of a substantially rectangular plate that may be attached to the under side of the stationary plate 8, which plate 8 constitutes the backing plate for the stationary teeth 5. The plate 7 is so attached to the base plate 8 of the stationary teeth at the under side thereof by means of upwardly and inwardly curved flanges 9, extending for the full width of the side edges and which form inwardly opening recesses wherein the opposite side edges of the plate 8 are received. The inner face of the plate 7 is provided with a plurality of transversely extending ridges 10, each of said ridges 10 terminating at the front edge of the plate in upturned teeth 11, the lower face of said plate being rounded transversely as at 12, and merging at its rear longitudinal edge into an upwardly and inwardly turned flange 13. It will be noted then, that when the plate is applied to the under surface of the base plate 8, the teeth 11 will extend between the teeth 5 and the rear portion of the plate due to its curve 12 is disposed in spaced relation to the under face of the plate 8 and is held firmly in position by means of its upturned inwardly directed flange 13, which engages the base portion of the plate 8.

When the attachment is disposed on the clippers as before indicated, it will be seen that the teeth 11 of the attachment extend between the teeth 5, but in such a manner as to strengthen the teeth of the clipper plate and

as not to interfere with the movable teeth 6. It is also to be noted that my plate may be adjusted to work in cooperation with the top plate as the lower plate is adjusted backward or forward to cut the hair long or short. Thus it will be seen that even with the attachment applied, the clippers are permitted to cut the hair just as short, as without the attachment. However, with my attachment the hair will be picked up in a uniform gradual taper and held the hair until the space between the teeth of the lower plate is open by movement of the movable teeth whereby the hair may be engaged between the teeth and the lower plate.

Various changes in the form, shape, size, and other minor details of construction may be made without departing from the spirit of the invention as herein described, or scope 20 of the appended claims.

What is claimed is:

1. The combination of a hair clipping device of the class described, of a plate of resilient material adapted to be disposed at the under 25 surface of the base of the clipping device, said plate having attaching flanges at the opposite ends thereof for engagement with the adjacent edges of the base of said clipping device, said plate being bent longitudinally so 30 that the forward edge of the plate rests against the under surface of the said base, said plate merging at its opposite edge into an upwardly and inwardly turned flange, yieldably engaging the under face of the base, said plate 35 being further provided with transverse ribs terminating at the first mentioned edge of the plate into substantially vertically disposed teeth extending upwardly between the stationary teeth of the cutting device for engaging the forward edge of the base of the cutting device.

2. The combination of a hair clipping device of the class described, of a plate of substantially rectangular configuration formed 40 of resilient material applicable to the under surface of the base of the clipping plate, said plate at opposite ends provided with attaching flanges for engaging with the ends of the base, and said plate gradually curving 45 upwardly toward one longitudinal edge thereof, substantially vertically disposed teeth integral with the plate at said one edge and extending upwardly therefrom for disposition between the stationary teeth of the cutting device for engagement with the adjacent edge of the base, and said plate at its 50 opposite longitudinal edge merging into an upwardly and inwardly turned flange adapted to yieldably engage the base of the cutting device.

In testimony whereof I affix my signature.
JOSEPH W. RAGAN.
